PRESSING MACHINE

Application filed July 15, 1927. Serial No. 205,916.

This invention relates to pressing machines, and more particularly to a machine for applying pressure to rubber foxing after it has been placed in position on a shoe.

5 The foxing is usually in the form of a rubber strip which extends around the shoe upper adjacent the sole and serves to more strongly unite the sole and upper, particularly in the case of a fabric upper. It also 10 waterproofs the lower part of a fabric upper and protects it against scuffing in use.

Heretofore it has been the common practice to apply the foxing strip to the shoe and then subject the strip to the action of a hand roller 15 to effect the desired adhesion between the strip and the shoe portions, but this consumes considerable time, the adhesion is not uniform, and in the case of white goods the handling increases the soiling. With fabric uppers it 20 is particularly difficult to obtain good adhesion.

It is one of the objects of this invention to overcome the foregoing difficulties and to provide means for applying to the foxing strip a 25 substantially uniform and normal pressure simultaneously throughout its entire length and width, thereby obtaining uniformity in adhesion and consequent evenness in the finished product. Another object is to provide a compact, simple, rapid and economical 30 apparatus for pressing shoe foxings or similar parts.

The invention comprises broadly a resilient body having an interior opening approximately of the size and contour of the article or portion to be pressed, means for circumferentially exerting pressure on the body to contract said opening around an article to be pressed, and means for constraining movement of said body to a plane substantially normal to the part to be pressed. The invention may also include means for exerting tension on the body to enlarge the opening 45 when desired.

Other features and advantages will appear as the description proceeds.

In the accompanying drawings:

Fig. 1 is a perspective view of the pressing 50 machine embodying my invention;

Fig. 2 is a vertical cross section of the machine; and

Fig. 3 is a fragmentary plan view of the rubber pressure element.

Referring to the drawings which illustrate 55 one practical example of my invention as applied to pressing shoe foxings, the reference character 10 represents a flat, relatively thick block or ring of resilient material, preferably of soft vulcanized or sponge rubber, 60 having a central opening or pocket 11 conforming substantially to the outline of the lower side portions of a shoe. The ring 10 rests upon the smooth surface 12 of a bottom plate 13, circular in the present instance, 65 having an annular side wall 14 upon which there is supported a circular cover 15 having a smooth interior surface 16 and also provided with a circular shoulder 17 which fits a complementary shoulder 18 of the plate 13, 70 a gasket 19 being provided to seal the joint between the shoulders. The depth of the side wall 14 is such that the ring 10 has a snug 75 sliding fit between the smooth surfaces 12 and 16, and the diameter of the circular side wall 14 is sufficiently greater than the diameter of the ring 10 to provide an annular space or chamber 20 completely around the ring. The cover 15 has a central opening 21, above the opening or pocket 11 of the ring 10, of elongated shape and somewhat larger than the opening 11, and the cover may be secured to the platform 13 by any suitable means such as fasteners 22.

In operation in the case of a shoe larger 85 than the opening 11 the air is first exhausted from the chamber 20, thereby permitting atmospheric pressure to expand the mass of the rubber ring 10 outward from the opening or pocket 11 and thus cause the same to enlarge. Place the shoe with applied foxing in position within the opening 11 and admit to the chamber 20 a pressure medium, such as compressed air, whereby the material of the ring 10 is compressed and moved bodily 90 inward, and the walls 11' of the opening 11 provide pressing faces which are caused to close against the foxing and thus press the same firmly against the portions of the shoe 95 to which it has been previously applied. Dur- 100

ing this operation the bottom plate 13 and the cover 15 provide guides for preventing buckling or shifting of the walls of the opening 11 across the direction in which pressure is applied to the article. It will be noted that those portions of the wall 11' which are to press the shank of the shoe are inwardly inclined at the bottom to more closely conform to the shoe. To carry out this operation there is provided a manifold pipe 23 which connects through branch pipes 24 and 25 to opposite sides of the annular chamber 20. The pipe 23 is attached to a pipe 26 which connects through a three-way valve 27 and pipe 28 to exhausting apparatus (not shown). The pipe 26 also connects through valve 27 to a pipe 29 which leads to a source of air pressure (not shown). An exhaust port 30 in the valve 27 may be utilized to admit air at atmospheric pressure to the chamber 20, after which the rubber ring 10 will be neither expanded nor compressed. A handle 31 is operable to control the three positions of the valve 27. In the present embodiment but two inlet connections 24 and 25 are shown to chamber 20, but any necessary number to secure even distribution may be used.

In order to maintain a pressure tight seal between the ring 10 and the surfaces 12 and 16 during the admission of fluid under pressure to the chamber 20, the outer edges of the ring 10 are provided with annular lips 32 which tend to spread under pressure and into contact with said surfaces and thereby prevent leakage. To prevent leakage during exhaustion of the chamber 20, provision is made for similar annular lips 33 formed by cutting away a portion of both the upper and lower surfaces of the ring or block 10, as indicated by the numeral 34. When air is exhausted from chamber 20 the pressure of atmospheric air on the lips 33 forces them against surfaces 12 and 16 to prevent leakage past ring 10. The cutting away of the ring at 34 also somewhat reduces the vertical thickness of the ring and renders it more responsive to pressure changes. In order to prevent buckling of the ring at the points of reduced thickness portions 34' of the full thickness are preferably left at spaced points.

For holding the shoe down within the opening 11 of the ring 10 during the pressing operation, there may be provided any suitable means such as the clamp illustrated in Fig. 1. This clamp includes a bridge piece 35 (shown in part only) spanning the cover 15 and having the legs thereof secured to said cover by means of a pair of the fasteners 22. A rod 36 passes through a vertical aperture in the center of the bridge piece 35 and carries at the lower end thereof a yoke 37 having an open slot 38 in which is pivoted at 41 an equalizing bar 39 equipped at its opposite ends with feet 40. A handle 42 is

secured to the top of the rod 36 and an expansion spring 43 is interposed between the handle 42, and the bridge piece 35. After inserting the shoe into the opening 11, the handle 42 may be operated to bring the feet 40 to bear against the shoe last and toe of the shoe and thereby hold the shoe during the pressing of the foxing strip. Any other desired means for securing the article during pressing may be used.

Different sizes of shoes vary considerably as to length while the variations in width are proportionately small. In order to take care of these variations, it is desirable that the opening 11 of the ring 10 be capable of changes in shape, that is, distending lengthwise a greater distance than crosswise. For accomplishing this purpose there are provided within the chamber 20 and at opposite sides of the ring 10, stops or blocks 44 which are substantially arcuate in form and are effective to check the expansion of those portions of the disc opposite the side walls of the opening 11 so that while the toe and heel portions of the opening 11 may expand freely toward the wall 14 in a lengthwise direction and thereby elongate the opening 11 to a considerable extent, the side walls of the opening are allowed to expand only to a desired amount. The blocks 44 are spaced from the parts 13 and 15 by ribs 44'. For supporting the machine and its controlling devices, there may be provided legs 45 secured to the under side of the platform 13 by fasteners 46. If desired, the responsiveness of the ring 10 to pressure changes may be further increased by making openings of desired shape in the body of the ring as shown at 47.

In pressing a foxing on a shoe, in the case where the shoe is larger than the opening 11, the operator turns valve 27 to connect the vacuum pump with the chamber 20, thereby expanding radially outward the ring 10 and enlarging the opening 11 sufficiently to place the shoe therein. He then pushes downwardly on the handle 42 to engage the feet 40 with the shoe last and toe of the shoe, and turns the valve 27 to admit pressure fluid to the chamber 20. This causes the ring 10 to contract, thereby contracting the opening 11 and causing the wall 11' of the opening to firmly and uniformly press the foxing on the shoe. The valve 27 is then again moved to connect the vacuum pump with chamber 20, the shoe removed and replaced by another and the operation is repeated. If the shoe is of a size small enough to directly enter the opening 11, it will be unnecessary to first expand the ring 10. The valve 27 when in its intermediate position places chamber 20 in communication with the atmospheric air inlet 30, hence in switching the chamber connections 24 and 25 from the vacuum line to the pressure line, or vice versa, the chamber 20 is necessarily placed in communication with the atmosphere as the

valve passes through its intermediate position. This reduces the load on the vacuum and pressure pumps.

By the use of the present invention, a large number of sizes can be taken care of on a single machine, and the parts are preferably arranged to press a pair of shoes simultaneously, either by duplication of the entire pressing device or by the provision of a block having two shoe receiving openings therein. Instead of expanding and contracting the ring 10 by pressure fluid any other suitable mechanical means may be employed. Fluid pressed flexible diaphragm machines have been previously used for pressing plied up rubber articles to secure better adhesion between the plies, but in such machines the actual pressing is accomplished by the fluid and the thin diaphragm acts merely as a restrainer for the fluid, and it is difficult to secure proper pressure at all points on articles of irregular contour. Moreover, the diaphragms quickly deteriorate, and as they stretch when inflated in contact with the article, they exert an undesirable frictional pull on the article at an angle to the direction of pressure, which tends to unite the plies when one or more of them are in a stretched condition. By the present invention, the pressing is directly accomplished by a relatively thick mass of material which is rigid enough to impart the desired firm pressure, but at the same time is yielding and resilient enough to properly conform at all points to the part to be pressed.

It will be seen that by my invention an apparatus has been provided for pressing rubber shoe foxings and similar articles, which is simple, efficient and easily operated, which can take care of a large number of sizes, and which is economical to build and operate and durable in use.

It is obvious that with the present detailed disclosure numerous modifications will suggest themselves to those skilled in the art, and it is not desired to limit the invention otherwise than as required by the prior art. The invention is not to be understood as being limited to a pressing appliance in which the element 10, of rubber or equivalent material, completely encircles the articles as obviously the pressure may also be applied partially or locally to the footwear at one or more points, for instance, at the heel or toe only or at the toe-cap, or other portions of the shoe or other article.

Having thus described my invention, what I claim and desire to protect by Letters Patent is:

1. A pressing machine comprising opposed walls, one of which has an article receiving opening, means for fixedly holding an article therein, resilient material disposed between said walls around said opening, and means for expanding or contracting said material.

2. A pressing machine comprising a block of resilient material having an opening for the reception of an article to be pressed, means disposed peripherally of the block for actuating it to vary the size of the opening, and means for limiting such variation for part of the opening.

3. A pressing machine comprising a block of resilient material having an opening for the reception of an article to be pressed, means disposed peripherally of the block for actuating it to vary the size of the opening, and guide means engaging the block at opposite sides for preventing lateral buckling of the block.

4. A pressing machine comprising a casing having an opening in its wall, a block of resilient material movable in the casing and having an opening aligned with said first opening, said block forming with the casing a fluid chamber peripherally of the block, means for varying the fluid pressure in said chamber, and means carried by the block for sealing said chamber.

5. A pressing machine comprising a casing having an opening in its wall, a block of resilient material movable in the casing and having an opening aligned with said first opening, said block forming with the casing a fluid chamber peripherally of the block, means for varying the fluid pressure in said chamber from sub to super atmospheric, and means carried by the block for sealing said chamber under either of said conditions.

6. A pressing machine comprising a relatively flat casing having an opening in its wall, a block of resilient material of lesser area disposed in said casing and forming therewith a chamber peripherally of the block, means for varying the pressure in said chamber, means carried by the block and engaging the casing walls for sealing the chamber, said block being formed, inwardly of the sealing means, to increase its responsiveness to pressure changes, and an article receiving opening in the block aligned with the casing opening.

7. A pressing machine comprising a resilient body having an elongated opening therein adapted to receive a part to be pressed, means disposed peripherally of the body for expanding or contracting the same to thereby expand or contract said opening, and limiting means for causing a proportionately greater lengthening than widening of the opening during variations of said opening.

8. A pressing machine including in combination, a pressure element in the form of a block of resilient material having an opening therein for reception of an article to be pressed, a housing for the block, said housing forming with said block a pressure-tight chamber therearound, while permitting free

sliding of the block, and means for exhausting or applying pressure to said chamber.

9. A pressing machine including in combination, a pressure element in the form of a block of resilient material having an opening therein for reception of an article to be pressed, a plate upon the surface of which one face of the block is adapted to rest, a cover mounted upon said plate and having its inner surface in contact with the opposite face of the block, both of said surfaces permitting free sliding of the block, said plate, the cover and the block combining to form a pressure-tight chamber around said block, and means for exhausting or applying pressure to said chamber.

10. A pressing machine including in combination, a pressure element in the form of a block of resilient material having an opening therein for reception of an article to be pressed, a plate upon the surface of which the lower face of the block is adapted to rest, a cover mounted upon said plate, means for spacing the inner surface of the cover from the surface of the plate in a manner to closely confine the block between the two surfaces while permitting free sliding of the block, said plate, the cover and the block combining to form a pressure-tight chamber around said block, a system of pipe connections communicating with said chamber, and a valve associated with said system and operable to selectively connect said system to a source of pressure or vacuum or to the atmosphere.

11. A pressing machine including in combination, a pressure element in the form of a block of resilient material having an opening therein for reception of an article to be pressed, means for causing the wall formed by said opening to close upon said article, means for causing said walls to recede from said article, and means for effecting a relatively greater recession at some portions of said wall than at others.

12. A pressing machine including in combination, a pressure element in the form of a block of resilient material having an opening therein for reception of an article to be pressed, means for causing expansion of said block in a manner to enlarge said opening, and means for checking said expansion at predetermined points whereby to alter the proportions of said opening when enlarged.

13. A pressing machine including in combination a pressure element of resilient material in the form of a block having an elongated opening therein for reception of an article to be pressed, means for causing expansion of said block in a manner to enlarge said opening, and a pair of stops disposed on opposite sides of said block in predetermined spaced relation thereto, said stops being located to meet the adjacent portions of the expanding block and hold them in check whereby to pre-

vent further widening of said opening while the other portions of the block continue to expand and effect a lengthening of said opening to a relatively large extent.

14. In an apparatus for pressing rubber articles including in combination a size-variable element for directly engaging the article, a housing in which said element is shiftably guided, and fluid pressure means for shifting said element in said housing. 70

15. In an apparatus for pressing rubber articles, in combination, an element of size-variable composition provided with an opening of the shape approximating the shape of the article to be treated, a housing in which said element is housed, and fluid pressure means for applying force to said element to enlarge and contract said opening whereby to receive, compress and release the article introduced in said opening. 80

16. In an apparatus for pressing rubber articles, in combination, a vulcanized rubber element for engaging the article, a member in which said element is bodily shiftably mounted, and means for applying sub-atmospheric and super-atmospheric pressures to said element to shift it and to press the element against the article. 85

17. In an apparatus for pressing rubber articles, in combination, an element of size variable material provided with an opening for the article to be pressed, and means for applying force in the plane of said material to contract or enlarge said opening. 95

Signed at New Haven, county of New Haven, State of Connecticut, this 11th day of July, 1927.
